UNITED STATES PATENT OFFICE.

JAMES WHALEY SHEPHERD, WILLIAM AYRTON, AND RALPH CLEGG, OF LONGSIGHT, NEAR MANCHESTER, COUNTY OF LANCASTER, ENGLAND.

TWISTING AND DOUBLING MACHINE.

SPECIFICATION forming part of Letters Patent No. 410,297, dated September 3, 1889.

Application filed April 19, 1887. Serial No. 235,303. (No model.) Patented in England January 30, 1886, No. 1,383, and in France December 6, 1886, No. 180,102.

To all whom it may concern:

Be it known that we, JAMES WHALEY SHEPHERD, WILLIAM AYRTON, and RALPH CLEGG, all of Longsight, near Manchester, in the county of Lancaster, England, have invented a new and useful Improvement in Twisting and Doubling Machines, of which the following is a specification, reference being had to the accompanying drawings.

10 The invention has been patented to us in Great Britain, No. 1,383, of January 30, 1886, and in France on the 6th of December, 1886, No. 180,102.

Our invention relates to machinery or apparatus for twisting or doubling, or twisting and doubling, slivers, yarns, or threads of cotton or other fibrous materials, certain portions of the apparatus being applicable for use in certain spinning-machines.

20 Our invention relates to machines in which the sliver, yarn, or thread, or slivers, yarns, or threads, to be operated upon is or are wound upon a bobbin or spool, or bobbins or spools, and also to machines in which the sliver, yarn, or thread, or slivers, yarns, or threads, to be operated upon is or are wound in the form of a cop or cops, and to machines in which the sliver, yarn, or thread, or slivers, yarns, or threads, after being operated upon, is or are wound upon a bobbin or spool, and to machines in which the sliver, yarn, or thread, or slivers, yarns, or threads, after being operated upon, is or are wound upon a spindle in the form of a cop.

30 For convenience of description we will first describe the arrangement of spindle and certain apparatus immediately connected therewith which we employ in those cases in which the sliver, yarn, or thread, or slivers, yarns, or threads, to be operated upon is or are wound upon a bobbin or spool, and also the arrangement of spindle and certain apparatus immediately connected therewith which we employ when the sliver, yarn, or thread, or slivers, 45 yarns, or threads, to be operated upon is or are wound in the form of cops. We shall then describe the arrangement of machinery or apparatus which we employ in conjunction with the spindle when the sliver, yarn, or thread, or 50 slivers, yarns, or threads, operated upon is or

are to be wound upon a bobbin or spool, and we shall then describe the arrangement of machinery or apparatus which we employ in conjunction with the spindle when the sliver, 55 yarn, or thread, or slivers, yarns, or threads, operated upon is or are to be wound into the form of a cop.

We will describe our invention by reference to the drawings hereunto annexed, in which drawings—

Figure 1 is a longitudinal section, Fig. 2 a side view, and Fig. 3 an end view, of a spindle carrying a bobbin on which the sliver, yarn, or thread, or slivers, yarns, or threads, to be operated upon is or are wound. Fig. 4 is a 65 longitudinal section, and Fig. 5 an end view, of a spindle carrying cops formed of the slivers, yarns, or threads to be operated upon. Fig. 6 is an end view, and Fig. 7 a partly-sectional side view, of a machine in which the 70 spindle is combined with mechanism by means of which the sliver, yarn, or thread, or slivers, yarns, or threads, after being operated upon, is or are wound upon a bobbin or spool. Fig. 8 is a side view, Fig. 9 a plan, and Fig. 10 an 75 end view, of a drag or draw roller which is used in conjunction with the spindle above mentioned. Fig. 11 is a partial front view, and Fig. 12 an end view, of a machine in which the spindle is combined with mechanism 80 by means of which the sliver, yarn, or thread, or slivers, yarns, or threads, after being operated upon, is or are wound into the form of a cop. Fig. 13 is a view showing

more clearly certain details shown in Fig. 12. 85 Fig. 14 is a view showing more clearly certain details shown in Figs. 11 and 12. Fig. 15 shows in plan certain parts shown in elevation in Figs. 12 and 13. Fig. 16 is a plan, and Fig. 17 an elevation, showing, upon a larger 90 scale, portions of that which is shown in Figs. 11, 12, and 13; and Fig. 18 is a plan, and Fig. 19 an elevation, showing certain parts which are partly, but imperfectly, shown in Figs. 11, 12, and 13.

In Figs. 1 and 2, *a* is a spindle mounted so as to be capable of being rotated in the collar *b* and foot-step *c*. Fast upon the spindle *a* is a warve *d*, by means of which the spindle *a* may be rotated. We mount a tube *e* loose 100

upon the spindle *a*. To the tube *e* we attach a cradle or frame *f*. The lower portion *f'* of the cradle or frame *f* is so formed that it will act as a weight and prevent the cradle or frame *f* from being rotated by the rotation of the spindle *a*. One edge *f''* of the cradle or frame *f* is formed curved. Longitudinally through a portion of the length of the spindle *a* we form a passage or tube *g*, which passage 10 or tube *g* extends from the end *a'* of the spindle *a* to openings *h*, formed through the sides of the spindle *a*. Fast upon the spindle *a* we secure a cup *j*, and fast upon the boss of the cup *j* we mount a disk *k*. Upon the cradle or frame *f* we form a projecting part *f''*, which 15 partly incloses the cup *j*.

The sliver or slivers and yarn or yarns and thread or threads to be twisted or doubled, or twisted and doubled, we shall, for simplicity, hereinafter call the "yarn."

The yarn *A* to be twisted or doubled, or twisted and doubled, is wound upon a bobbin *l*, which is placed upon the tube *e*. The yarn *A* to be twisted or doubled, or twisted and doubled, is conducted from the bobbin *l* over the curved edge *f''* of the cradle or frame *f*, then along the outer surface of the said cradle or frame *f*, and then over the end *f''* of the cradle or frame *f* to the end *e'* of the tube *e* and 25 along the passage or tube *g*, then through either of the openings *h* and over the edge *k'* of the disk *k*, from which the said yarn *A* passes to a drag or draw roller, as we will hereinafter describe. We provide the cradle or 30 frame *f* with a ring *f''*, which prevents the yarn *A* from coming into contact with the bobbin *l*. When all the yarn wound upon the bobbin *l* has been removed therefrom, such bobbin *l* may be drawn off the tube *e* through 35 the ring *f''*, and another bobbin having yarn wound thereon may be passed through the ring *f''* and onto the tube *e*.

The yarn *A* to be twisted or doubled, or twisted and doubled, in its passage from the bobbin *l* to the passage or tube *g*, formed in the spindle *a*, receives one amount of "twist," and while passing from the spindle *a* to the drag or draw roller above mentioned receives a further amount of twist. The end *e'* of the 40 tube *e* passes into the interior of the cup *j*, and the part *j'* of the cup *j* passes into a cavity formed by the projecting part *f''* upon the cradle or frame *f*. The cup *j* and projecting part *f''* prevent oil from the spindle *a* from 45 getting upon the yarn *A* while such yarn *A* is being twisted or doubled, or twisted and doubled.

Figs. 4 and 5 show an arrangement of our invention which we employ for twisting 50 or doubling, or twisting and doubling, yarn which has been wound into cops. To the cradle or frame *f* we secure pegs or skewers *m*, upon which the cops *B B'* are placed. At the end *f''* of the cradle or frame *f* we attach 55 guides *o o'*, which are hinged to the cradle or frame *f*. The remaining ends of the guides

o o' are each formed with an eye *o''*. When the guides *o o'* are turned upon the hinged part *p*, cops *B B'* may be placed upon the pegs or skewers *m*, and after the cops *B B'* have been placed upon the pegs or skewers *m* the guides *o o'* may be again placed in the position in which they are shown in the drawings.

The yarn *C* to be twisted or doubled, or 75 twisted and doubled, is passed from the cop *B* through the eye *o''* of the guide *o* and from the cop *B'* through the eye *o''* of the guide *o'*. The yarn *C* from both of the cops *B B'* is passed through the passage or tube *g* and 80 either of the openings *h* and over the edge *k'* of the disk *k*, as previously described in reference to the arrangement in which the yarn to be twisted or doubled, or twisted and doubled, is wound upon a bobbin *l*. The yarn 85 *C* from the cops *B B'* will, by the rotation of the spindle *a*, receive one amount of twist in passing from the cops *B B'* to the end *a'* of the spindle *a*, and in passing from the edge *k'* of the disk *k* to the drag or draw roller will 90 receive an additional amount of twist. By means of the arrangements above described we are enabled to give to the yarn operated upon two turns of twist for every turn of the spindle employed.

Having now described the arrangement of apparatus by which we are enabled to impart to the yarn two turns of twist for each turn of the spindle *a*, we will now describe such apparatus as combined with certain 100 other mechanism by means of which we wind the yarn upon a bobbin after it has been twisted or doubled, or twisted and doubled.

Figs. 6 and 7 show so much of a machine as is requisite to illustrate this application of 105 our invention.

In Figs. 6 and 7, *q r* are end frames. To the end frame *r* is secured one end of each of the rails *s t*, the remaining ends of which are secured to another frame similar to the frame *r*. The rails *s t* support the foot-steps *c* and collars *b*, which support the spindles *a*. To the rails *u v*, which are secured at one end to the end frame *r*, we secure troughs *w x*, in which are shafts *y z*, respectively capable of 115 being rotated in bearings, one only of which bearings is shown in the drawings. Upon the shafts *y z* grooved pulleys *1* are secured. 2 is a "tin drum," which is driven by means of a strap *3* from any convenient source of 120 motive power. The spindles *a* are driven by means of the bands *4*, which pass around the tin drum *2* and waryes *d* and partially around a tin drum *5*, which is mounted upon a shaft *6*, mounted in suitable bearings mounted 125 upon the end frames of the machine, and acts as a guide to the bands *4*.

Upon the axle *2'* of the tin drum *2* is a wheel *7*, the teeth of which take into or engage with the teeth of a wheel *8*, carried upon 130 a stud *9*. Secured to the wheel *8* is a wheel *10*, the teeth of which gear into or engage

with the teeth of a wheel 11, mounted upon a shaft 12, extending lengthwise of the machine.

13 is a shaft extending lengthwise of the machine, which shaft 13 receives rotary motion from the shaft 12 by means of the cross-shaft 14 and bevel-wheels 15 16 17 18.

Fast upon the shaft 13 is a bevel-wheel 19, the teeth of which gear into or engage with the teeth of a bevel-wheel 20, fast upon the lower end of a vertical shaft 21, supported by brackets. Fast upon the upper end of the vertical shaft 21 is a bevel-wheel 22, the teeth of which gear into or engage with the teeth of a bevel-wheel 23, fast upon a horizontal shaft 24, which shaft 24 is carried in brackets. Upon opposite ends of the shaft 24 are bevel-wheels 25 26, the teeth of which gear into the teeth of wheels 27 28, respectively mounted fast upon the shafts 29 30, extending lengthwise of the machine.

Above each of the spindles 31, which are supported by rails 32, is a drag or draw roller 33, fast upon a short shaft 34, capable of being rotated in a bracket 35, secured to the rail *u* or the rail *v*, as the case may be. Fast upon the short shaft 34 is a bevel-wheel 36, the teeth of which gear into or engage with the teeth of a bevel-wheel 37, fast upon the shaft 29 or 30, as the case may be. Beneath the drag or draw roller 33 is a finger 38, secured by a set-screw 39 to the bracket 35. The drag or draw roller 33 and the finger 38 are shown more clearly in Figs. 8, 9, and 10, in which figures Fig. 8 is a side elevation, Fig. 9 a plan, and Fig. 10 a front view, of the drag or draw roller 33 upon an enlarged scale. The edge 38^a of the finger 38 is formed inclined to the axis of the drag or draw roller 33. The rotation of the tin drum 2 will, by means of the wheels 7 8 10 11, shaft 12, bevel-wheels 15 16, shaft 14, wheels 17 18, shaft 13, bevel-wheels 19 20, shaft 21, bevel-wheels 22 23, shaft 24, bevel-wheels 26 28 and 25 27, shafts 29 30, bevel-wheels 37 36, and short shafts 34, cause each of the drag or draw rollers 33 to be rotated in the direction indicated by the arrow *D*. The yarn *A* from the bobbin *l*, after being passed over the edge *f*² of the cradle or frame *f*, is conducted past the end *f*⁴ of the cradle or frame *f*, through the passage or tube *g* and one of the openings *h*, and over the edge *k*² of the disk *k*, from which it passes through a guide 40, secured to a bar 41, secured to the trough *w* or the trough *x*, as the case may be. The yarn *A* then passes over one of the pulleys 1 and over a guide-rod 42 to the drag or draw roller 33, around which and the finger 38 it is passed one or more times, as may be requisite. The yarn *A* is then conducted under a faller-wire 43, carried by a faller 44, to be wound upon the bobbin *E*, which is mounted upon a spindle 31. The grooved pulleys 1 are driven by the yarn or thread passing over them.

Upon the shafts 12 13 are mounted tin

drums 45, which, by means of bands 46, impart rotary motion to the spindles 31. The spindles 31 are rotated at a speed in excess of that required to take up the yarn delivered by the drag or draw rollers 33 and drive or rotate the bobbins *E* by means of the friction between the flanges 31^a upon the spindles 31 and the bases of the bobbins *E*, placed upon the said spindles 31. The inclined or curved edge 38^a of the finger 38 causes the yarn *A*, while being drawn from the bobbin *l*, to pass around the drag or draw roller 33 in an open spiral and prevents one coil of yarn from passing over a neighboring coil. The yarn is passed as many times around the drag or draw roller 33 as may be requisite to draw the yarn from the bobbin *l*.

The yarn is guided to or "built" upon the bobbins *E* by means of the faller-wires 43, which faller-wires 43 are actuated by means of the heart or cam 47. The heart or cam 47, which receives motion by means of the shaft 47^a, worm-wheel 47^b, and worm 47^c from the shaft 21, acts upon a bowl or roller 48, carried by a lever 49, connected by a rod 50 to a lever 51, secured to a shaft 52, to which the faller 44 is secured.

To the lever 51 is jointed one end of a rod 53, which at its other end is jointed to a lever 54, fast upon the shaft 55, upon which shaft 55 is fastened an arm 56, which carries the faller-wire 43 on the opposite side of the machine. The rotation of the heart or cam 47 imparts to the faller-wires 43 the motion required to "build" the yarn *A* upon the bobbin *E*. If after the yarn has been twisted or doubled, or twisted and doubled, as above described, it is desired to wind such yarn upon a spindle in the form of a cop, we employ the arrangements shown in Figs. 11, 12, and 13.

To avoid confusion, certain parts are omitted from Figs. 11, 12, and 13. To such of the parts shown in Figs. 11, 12, and 13 as correspond to parts hereinbefore referred to we shall affix the same letters of reference as we have affixed to the parts corresponding thereto. In Figs. 11 and 12, 57 58 are end frames. To the end frame 58 are secured rails *s t*, which carry the spindles *a*, each provided with a cradle or frame *f*. To the end frame 58 are secured rails *u v*, which support troughs *w x*, carrying shafts *y z*, upon which are mounted pulleys 1. Upon the rails *u v* are mounted drag or draw rollers 33. The rails *s t u v* are secured at their ends which are not shown in the drawings to an end frame similar to the end frame 58.

59 60 are rails which support spindles 61.

2^a is a shaft which receives rotary motion from any convenient source of motive power. Upon the shaft 2^a is mounted a tin drum 2, which imparts rotary motion to the spindles *a* by means of the bands 4, which bands 4 are guided upon the warves *d* of the spindles *a* by means of the tin drum 5.

62 are faller-wires carried by arms 63,

mounted upon faller-shafts 64, supported in bearings carried by the end frame 58 and the other end frame of the machine.

65 is a counter faller-wire carried by arms 5 66, secured to a counter faller-shaft 67, supported by the end frame 58 and the other end frame of the machine.

68 is a shaft capable of being revolved in bearings carried by the end frames 57 58.
10 Mounted upon the shaft 68 so as to be capable of being rotated thereon is a cone-drum 69, which receives rotary motion from the shaft 2^a by means of the toothed wheels 63^a 64^a 65^a 66^a.

15 Fast with the cone-drum 69 is a toothed bevel-wheel 70, the teeth of which gear into the teeth of a bevel-wheel 71, carried by a bevel-wheel 72, mounted upon the shaft 68 so as to be capable of being rotated thereon.

20 The teeth of the bevel-wheel 71 gear into the teeth of a bevel-wheel 73, mounted upon the shaft 68 so as to be capable of being rotated thereon. Fast with the bevel-wheel 73 is a toothed wheel 74, the teeth of which gear

25 into or engage with the teeth of a wheel 75, mounted fast upon a shaft 76, mounted fast upon which is a tin drum 77, which, by means of endless bands 77^a, imparts rotary motion to the spindles 61.

30 78 is a shaft capable of being rotated in bearings formed in the end frames 57 58. Fast upon the shaft 78 is a cone-drum 79, which receives rotary motion from the cone-drum 69 by means of a strap 80. The cone-drum 79,

35 the bevel-wheels 79^m and 79ⁿ, short shaft 79°, and bevel-wheel 79^p impart motion to the bevel-wheel 72. The wheels 70, 71, 72, and 73 constitute a "differential motion," similar to that used in the machines known as "rowing" or "slubbing" frames, by which differential motion the rotation of the tin drum 77 may be governed, as will be hereinafter described.

In the end frames 57 58 are formed bearings, 45 supported by and capable of being revolved in which is a shaft 81, upon which are formed screw-threads 81^m, mounted upon which and capable of being traversed thereon and thereby is a strap-guide 82, between the forked 50 ends of which the strap 80 passes.

To one faller-shaft 64 is secured an arm 83, formed with a curved part 83^a, to the end of which is connected a chain 84, the other end of which is connected to a curved part 85^a, 55 formed upon one arm 85 of a bell-crank lever mounted so as to be capable of being oscillated upon a stud 86, carried by the end frame 58. One arm 87 of the bell-crank lever aforesaid is provided with a bowl or roller 88, which 60 is supported upon a shaper bar or plate 89, carried upon a frame 90, capable of being slid longitudinally in V-guides 91, formed upon a bracket 92, secured to the end frame 58. The frame 90 and certain of the parts 65 connected therewith are shown more clearly in Fig. 14, which will be hereinafter more particularly described in reference to a further

part of our invention. Secured to the frame 90 is a stud 93, which carries a bowl or roller 94, against which acts a cam 95, mounted fast 70 upon a shaft 96, mounted so as to be capable of being rotated in bearings formed in the end frame 58. The shaft 96 receives rotary motion by means of the worm-wheel 97, worm 98, and bevel-wheels 99 100, the latter of which 75 is fast upon the shaft 68. As the cam 95 rotates it will, by means of the bowl or roller 94, cause the frame 90 to be slid to and fro in the brackets 92, and by means of the shaper bar or plate 89, as will be readily understood 80 by persons acquainted with machines for "building" yarn into cops, will by means of the bowl or roller 88, arms 87 85, chain 84, and arm 83 raise the faller-wires 62 upon one side of the machine and allow them to descend, so as to guide the yarn while being wound upon the spindle 61. The yarn A to be wound upon the spindles 61, after leaving the drag or draw rollers 33, passes beneath the counter faller-wires 65, and from the counter 90 faller-wires 65 passes over the faller-wires 62, from which it passes to the spindles 61. The drag or draw rollers 33 deliver the yarn A to the spindles 61 at a uniform speed, and in order that the spindles 61 may "take up" the 95 yarn A as it is delivered by the drag or draw rollers 33 we employ the arrangements to be next described, by means of which arrangements the speed at which the spindles 61 are rotated may be increased or decreased, as may 100 be required, in order to wind the yarn A into cops upon the spindles 61. In order that this portion of our invention may be readily understood we show in Fig. 13 certain parts in positions different from those in which they are 105 indicated in Figs. 11 and 12. The counter-faller 66 is weighted, so that it tends to turn in the direction indicated by the arrow F by means of a weight or spring, (not shown in the drawings,) which weight or spring is proportioned to the tension required in winding 110 the yarn upon the spindles 61.

Fast upon one of the faller-shafts 64 are arms 101 102, to which are jointed catches 103 104, respectively. Fast upon the catch 103 is 115 a lever 105, and fast with the catch 104 is a lever 106. To the lever 105 is jointed one end of a rod 107, the remaining end of which is jointed to a rod 108. To the lever 106 is jointed one end of a rod 109, the remaining end of which is 120 jointed to a rod 110. The lower ends of the rods 108 110 pass through holes formed through a bracket 111, which bracket 111 acts as a guide for the said lower ends of the rods 108 110. Fast upon the shaft 81 are two ratchet-wheels 112 113, placed side by side, the teeth of which 125 ratchet-wheels 112 113 are placed in opposite directions. The ratchet-wheels 112 113 are shown in the detached view, Fig. 15.

Near to the lower end of the rod 108 is jointed 130 a catch or pawl 114, the weight of which at certain times, as will be hereinafter pointed out, causes the catch or pawl 114 to engage with the teeth of the ratchet-wheel 112. Near

to the lower end of the rod 110 is jointed a catch or pawl 115, which catch or pawl 115 is caused at times, as will be hereinafter pointed out, to engage with the teeth of the ratchet-wheel 113. At the upper end of the rod 108 is formed a tooth 116 and at the upper end of the rod 110 is formed a tooth 117.

To the end frame 58 is secured a stud 118, upon which and capable of being oscillated thereon is a boss 119, upon which are formed arms 120 121 122. To the end frame 58 is secured a stud 123, upon which and capable of being rotated thereon is a boss, to which is secured a toothed wheel 124, which receives rotary motion by means of the wheel 125, fast with which is a wheel 125^m, which gears into a wheel 68^m, fast upon the shaft 68. Upon the stud 123 and fast with the toothed wheel 124 is mounted a cam 126, which acts upon a bowl or roller mounted upon the arm 121, fast upon the boss 119. As the cam 126 rotates, the arm 121 will be oscillated by means of the cam 126 in the direction indicated by the arrow G and will be oscillated in a direction opposite to that indicated by the arrow G by means of a spring 127, one end of which is secured to the arm 120, the remaining end of the spring 127 being secured to the end frame 58.

Upon the extremity of the arm 120 is formed a tooth 128, which at times, as will be hereinafter pointed out, is caused by the oscillations of the arm 120 to act upon one or other of the rods 108 110, so as to draw it in the direction indicated by the arrow H. Fast upon the shaft 96 is a disk 129, a portion of the circumference of which disk 129, between the points J and K, is removed in order that a recess, into which may pass a bowl carried by the arm 122, may be formed.

Secured to the end frame 58 is a stud 130, mounted upon which so as to be capable of being oscillated thereon is a bell-crank lever, one arm 131 of which is in contact with the circumference of a cam 132, mounted upon the stud 123 and fast with the toothed wheel 124. The arm 133 of the bell-crank lever aforesaid is situated beneath the ends of the levers 105 106, and at certain times, as will be hereinafter pointed out, will raise the ends of the said levers 105 106, and with them the ends of the rods 108 110. When the machine above described is at work, the yarn A, in its passage from the bobbins l to the drag or draw rollers 33, will have been twisted or doubled, or twisted and doubled, as hereinafter described, and will by the rotation of the spindles 61 be wound thereon. So long as the yarn A is wound upon the spindles 61 at the same rate as it is delivered by the drag or draw rollers 33, the counter faller-wires 65, by rising and falling between the points L and M, will compensate for the variations of the rate at which the yarn A is wound upon the smaller or larger parts of the cop. If the yarn A be taken up by the spindles 61 at a rate greater than that at which it is delivered by the drag or draw rollers 33, the counter

faller-wires 65 will be caused to arrive beyond the point M, and by means of an arm 134, rod 135, and arm 136 turn a part 137 in the direction indicated by the arrow N, and so move the part 137 from beneath the catch 103, when the rod 107, being no longer supported, will descend and bring the tooth 116 into the path of the tooth 128, so that each oscillation of the arm 120 in the direction opposite to that indicated by the arrow G, will be caused to draw the rod 108 in the same direction, and by means of the catch or pawl 114 and ratchet-wheel 112 rotate the shaft 81, and by means of the screw-threads formed on the said shaft 81 traverse the strap-guide 82 and the strap 80 from a larger to a smaller part of the cone-drum 69, and by means of the cone-drum 79, bevel-wheels 79^m 79ⁿ, shaft 79°, bevel-wheels 79^p 72 70 71 73, wheels 74 75, shaft 76, and tin drum 77 reduce the speed of the spindles 61, and thereby reduce the rate at which the yarn A is wound upon the spindle 61. The reduction of the rate at which the yarn A is wound upon the spindles 61 will allow the counter faller-wires 65 to descend to their normal position. The oscillations of the arm 133, caused by means of the cam 132, will lift the catch 103 to the level of the top of the part 137, and as soon as the descent of the counter faller-wires 65 turns the part 137 into position to support the catch 103 the tooth 116 will be raised clear of the tooth 128 on the arm 120. If the yarn A be taken up by the spindle 61 at a rate less than that at which it is delivered by the drag or draw rollers 33, the counter faller-wires 65 will descend below the point L, and will by means of the arm 134, rod 135, and arm 136 put the part 137 clear of the catch 104, and thus allow the arm 134, rod 109, and rod 110 to descend and allow the tooth 117 to pass into the path of the tooth 128 upon the arm 120, which, being oscillated by the cam 126, as hereinbefore described, will, when moving in the direction opposite to that indicated by the arrow G, draw forward the rod 110 in the direction indicated by the arrow H, and by means of the catch or pawl 115 and ratchet-wheel 113 and screw-threads formed upon the shaft 81 will traverse the strap-guide 82, so as to traverse the strap 80 from a smaller to a larger part of the cone-drum 69, and by means of the cone-drum 79, bevel-wheels 79^m 79ⁿ, shaft 79°, bevel-wheels 79^p 72 70 71 73, wheels 74 75, shaft 76, and tin drum 77 cause the spindles 61 to rotate with an increased velocity, and by so doing wind the yarn A upon the spindles 61 at a greater rate. The increase in the rate at which the yarn A is wound upon the spindles 61 will cause the counter faller-wires 65 to ascend to their normal position, so as to turn the part 137 into position to support the catch 104, rod 109, and rod 110, and the tooth 117, having been raised by the cam 132 and arm 133 of the bell-crank lever aforesaid, will also have raised the rod 110 and tooth 117 clear of the tooth 128 on

the arm 120, and the ratchet-wheel 113 will cease to be acted upon. The weight of each of the rods 108 110 causes it to move in the direction opposite to that indicated by the arrow H. The movement of the rods 108 110 in the direction opposite to that indicated by the arrow H is limited by means of projections 108^a 110^a, formed upon the rods 108 110, respectively. The disk 129 is fixed in such position upon the shaft 96 that the recess between the points J and K arrives opposite the bowl on the arm 122 at such times only as the faller-wires 62 are at about half of their "lift" between the largest and smallest parts of the cop. When the bowl on the arm 122 is in contact with the part of the circumference of the disk 129 situated between the points K and J, and the bowl on the arm 121 is held clear of the cam 126, no motion is imparted to the rods 108 110. The faller-shaft 64 on one side of the machine, by means of the arm 138 and chain 139 and arm 140, actuates the faller-shaft 64 and faller-wire 62 at the other side of the said machine, and the counter faller-shaft 67 at one side of the machine, by means of the arm 141, chain 142, and arm 143, actuates the counter faller-shaft 67 at the other side of the said machine.

A further part of our invention consists in 30 an arrangement of "copping motion," to be used in conjunction with the above-described or any other arrangements of machinery or apparatus for twisting or doubling, or twisting and doubling, slivers, yarns, or threads. 35 This portion of our invention is shown in Figs. 11, 12, and 14. In Fig. 14 our arrangement of copping motion is shown separated from the other parts of the machine. 90 is a frame supported by V-guides 92, in which it may be slid 40 longitudinally in the direction indicated by the arrow O by means of the cam 95, which acts against the bowl or roller 94 upon the stud 93, projecting from the frame 90. The frame 90 may be traversed in a direction opposite to that indicated by the arrow O by means of a weight or spring. (Not shown in the drawings.) Supported by the frame 90 are two inclines 144 145, which are formed with parts 146, which embrace V-guides 147, formed upon the 45 frame 90. Formed upon the frame 90 is a boss 148, through which passes a short shaft 149, capable of being rotated in the boss 148 and prevented from moving longitudinally by collars. Upon part of the short shaft 149 are 50 formed screw-threads 150, which take into or engage with screw-threads formed in a part 151, secured to the inclines 144 145. Mounted upon the short shaft 149 is a ratchet-wheel 152. Formed upon or secured to the frame 90 55 is an arm in which is formed a slot 153. 89 is a shaper bar or plate, which is provided with projecting parts 154 155, by which such shaper bar or plate 89 is supported upon the inclines 144 145. The projecting part 154 60 passes into the slot 153. As the frame 90, above mentioned, is moved to and fro by the

cam 95 and weight or spring above referred to, the shaper bar or plate 89 is traversed below the bowl or roller 88, carried by the arm 87, which, by means of the chain 84, actuates the faller-shaft 64. As the frame 90 is caused by the cam 95 to traverse to and fro, the ratchet-wheel 152 is caused to be rotated by means of the bell-crank lever 156 and clicks or pawls 156^a carried thereby, as will be well understood by persons conversant with the machines known as "self-acting mules." Secured to the bracket 92 is a bracket 92^m, the upper edge of which is formed with an incline 92ⁿ. When the arm of the bell-crank 80 lever 156 resting upon such incline 92ⁿ is traversed along said incline by the movement of the frame 90 in a direction opposite to that indicated by arrow O, the pawls or clicks upon the bell-crank lever 156 will 85 cause the ratchet-wheel 152 to be turned. The rotation of the shaft 149 will, by means of the screw-threads 150, cause the inclines 144 145 to be moved upon the frame 90 in the direction indicated by the arrow P, thus causing the shaper bar or plate 89 to be raised and act upon the faller-wire 62, so as to cause a cop to be built or formed in the form desired, the form of the cop being controlled by the contour of the shaper bar or plate 89 and 95 those of the inclines 144 145.

If it be desired, a still further amount of twist may be imparted to the yarn after such yarn has left the drag or draw roller above mentioned by the employment of an ordinary ring traveler and spindle for taking up the yarn delivered by the before-mentioned drag or draw roller; or a spindle and flier may be used for the same purpose.

In some cases, when the yarn, after being 105 twisted or doubled, or twisted and doubled, by any of the above-described arrangements, is wound upon a bobbin or tube by means of any of the arrangements ordinarily employed in drum-winding machines, the drag or draw 110 roller above mentioned may be dispensed with.

In some cases we form the disks k, hereinbefore mentioned, with eyes or curls, through one of which the sliver, yarn, or thread being operated upon may be passed, and in some 115 cases we employ arms instead of disks k, which arms may be formed with eyes or curls, through which the sliver, yarn, or thread being operated upon may be passed.

What we claim as our invention, and desire 120 to secure by Letters Patent, is—

1. The combination of parts herein described, by means of which more than one turn of twist is caused to be imparted to the sliver, yarn, or thread operated upon during 125 each revolution of the spindle employed, which combination of parts consists in a spindle, such as a, provided with a tube or passage, such as g, a disk, such as k, or equivalent therefor, a tube, such as e, a cradle or frame, 130 such as f, provided with a ring, such as f^a, and curved edge, such as f², all constructed, ar-

ranged, and operating substantially in the manner and for the purposes hereinbefore set forth.

2. The combination of parts herein described, by means of which more than one turn of twist is caused to be imparted to the sliver, yarn, or thread operated upon during each revolution of the spindle employed, which combination of parts consists in a spindle *a*, provided with a tube or passage, such as *g*, disk, such as *k*, or equivalents therefor, tube, such as *e*, cradle or frame, such as *f*, provided with guides *o* and *o'*, and pins or pegs, such as *m*, all constructed, arranged, and operating substantially in the manner and for the purposes hereinbefore described.

3. The combination of parts by means of which the sliver, yarn, or thread twisted or doubled, or twisted and doubled, is caused to be wound upon the spindle upon which the cop is to be wound at or about the same rate as it is delivered by the drag or draw roller employed, which combination of parts consists in faller-wires, such as *62*, faller-shaft, such as *64*, spindles, such as *61*, counter faller-wires, such as *65*, arms, such as *63*, arms, such as *66*, arm, such as *134*, rod, such as *135*, arm, such as *136*, part such as *137*, catches, such as *103* and *104*, levers, such as *105* and *106*, rod, such as *107*, rod, such as *109*, rod, such as *108*, pro-

vided with a tooth, such as *116*, rod, such as *110*, provided with a tooth, such as *117*, bracket, such as *111*, catches or pawls, such as *114* and *115*, ratchet-wheels, such as *112* and *113*, shaft, such as *81*, provided with screw-threads, such as *81^m*, a strap-guide, such as *82*, a strap, such as *80*, cone-drums, such as *69* and *79*, bevel-wheels, such as *70* *71* *73*, wheels, such as *74* and *75*, shaft, such as *76*, tin drum, such as *77*, arm, such as *120*, provided with a tooth, such as *128*, spring, such as *127*, cam, such as *126*, disk, such as *129*, arms, such as *131* and *133*, cam, such as *132*, bevel-wheels, such as *79^m* and *79ⁿ*, shaft, such as *79°*, bevel-wheel, such as *79^p*, wheel, such as *68^m*, wheel, such as *125^m*, wheel, such as *125*, wheel, such as *124*, bevel-wheel, such as *100*, bevel-wheel, such as *99*, worm, such as *98*, and worm-wheel, such as *97*, all constructed, arranged, and operating substantially in the manner and for the purposes hereinbefore described.
